JIGGER

Hans Willi Mettler, Geneva, Switzerland

Application April 11, 1932, Serial No. 604,489
In Switzerland April 15, 1931

1 Claim. (Cl. 8—19)

The present invention relates to a new and improved dyeing machine for textile fabrics and more especially to that type of dyeing machine which is known as a jigger.

5 With the hitherto known jiggers for the dyeing of webs of fabric the disadvantage has existed that with direct positive winding up of the fabric, the tension to which the fabric had to be subjected was too great, and fragile fabrics were 10 unduly strained and very frequently damaged. The speed of the fabric and with it the tension on the fabric was furthermore not constant; creasing frequently took place in both longitudinal and transverse directions of the web.

15 The object of the present invention is to overcome these defects and this is attained by causing the webs of fabric at no point of its passage through the vat being exposed to any appreciable tension.

20 According to the invention, the fabric is conveyed by a drum running in the vat and driven by a motor and is taken up by a rolling-on reel the position and circumferential speed of which is so chosen with respect to the feed of the fabric 25 that the circumferential speeds of the unwinding and the winding up reels are the same and separate guiding devices for the conveyor drum and the said reels are used so that the fabric is not subjected to any detrimental degree of tension 30 or stretching.

All rollers, drums and the like with which the material comes into contact have a special drive without the fabric being utilized in any way for this purpose, or being stressed with the result 35 that the finest and most fragile fabrics can be dyed without being injured.

Two embodiments are shown, to some extent diagrammatically, in the accompanying drawings and by way of examples:

40 Fig. 1 shows a jigger with hydraulic drive, in side view, partly in section.

Fig. 2 is an end view with some parts in section.

Fig. 3 shows a hydraulic driving motor in section and is taken on the line A—A of Fig. 1.

45 Fig. 4 shows a second form of construction with friction wheel drive, in side elevation.

Fig. 5 is an axial section of the same machine.

Fig. 6 shows diagrammatically the working process.

50 A drum 1 of comparatively large diameter is fitted on a shaft 2 (Figs. 1-3) which is rotatably carried on ball bearings 3 in the machine frame. The drum 1 is driven through toothed wheel and chain drive 5, 6, 7, 8 by a water turbine 9 or 9a.

55 The wheels of the turbines 9, 9a driven by means

of water jets are provided with oppositely directed blades which permit an alteration of direction of rotation of drum 1, the one or the other being used for driving. A reversible electric motor, not shown, a compressed air motor, or a weight motor or the like could be provided, in any case only such means for driving are used which allow the direction of rotation to be altered and ensuring a steady elastical drive. Water is supplied by a pipe 20 and nozzles directing jets on 10 to the wheels of said turbines 9, 9a. Valves are arranged in said pipe 20 to direct the flow of water to any of said turbines.

Alongside the drum 1, and parallel thereto there are fitted in ball bearings 12 both a rolling 15 up and a rolling-off reel 10, 11 by means of shafts 13. The bearings are slidably mounted in slots of the frame running radially with reference to the drum 1. The reels 10, 11 are mounted in such a manner that the reels never come into 20 contact with the drum 1. The reels 10, 11 also are of large diameter, and are easily rotatable on the ball bearings 12.

On each of the shafts 13 there are two water 25 wheels 14 one on each end (or a fan or electro-motor could be used for pneumatic or electric drive respectively).

The drum 1 is driven by one or the other turbines 9 or 9a, and by varying the quantity of water flowing through, the torque and thus the 30 speed at which the fabric passes the machine can be very easily regulated. The water under pressure used for the drive is, after giving up its power, caught at the outlet of the respective turbines in the pipes 21, 21a. In these pipes 21, 35 21a, there are light load or overflow connections as 22, which are controlled by regulating cocks 23. These regulating cocks 23 serve to regulate the flow of water to the water wheels 14 constantly for the rolling-up reel only, and to thus 40 exactly adjust the rotation of the rolling-up reel that the fabric fed by the conveyor drum 1 is very loosely rolled up without undergoing tension or stretching. Preferably, the water acts 45 upon the blades 14 only by gravity.

Slip couplings could also be used in the driving of the reels in order to be able to transmit a definite turning moment capable of adjustment.

In order to ensure a uniform dyeing of the 50 length of fabric on the machine even with the most moderate size dyeing bath, and in order to rapidly dye material not easily permeable, by squeezing in the dye, three very light rollers 25, 26, 27 made to float, are arranged easily rotatable 55 in the trough 24; the floating roller 27 is so ar-

ranged in loose bearings, that it can never bear against the conveyor drum 1, but automatically adjusts itself exactly parallel thereto. The floating rollers 25, 26 are pressed by buoyancy against the drum 1. The pressure of these floating rollers 25, 26 on said drum 1 can be regulated by varying the dimensions or weight of the rollers. The material, since it is carried over the roller 27, is held from the drum 1, thus giving the dye liquor better access to the fabric length.

In the dyeing of fabrics, as for example crepe and the like, these on becoming wet at once shrink in length and width. Even with a small pull on the fabric caused, for example, by the resistance of the ball bearings or the friction in the dye liquor, creases are produced. In order to prevent this creasing, a spreading device 28, 29, 30 is fitted in front of each fabric reel and in such a manner that this immerses wholly or partially into the dye liquor. Each spreading device consists of two pairs of very light cone rollers 28-30, with the greatest diameter in the point of contact in the centre of the path of the fabric web, and of two pairs of cone rollers 29 which are fitted on a bent and rocking spindle, the greatest diameter of the cones being at the outside on the edge of the fabric length. Spreading devices of this type are well known, any suitable device can be used.

30 The cone rollers can be adjusted as desired with respect to each other in order to adjust the embracing arc to the desired spreading out effect. The cones 29 here work as spreaders of the weft threads, and the cones 28, 29, 30, serve to smooth out the uneven warp thread lengths. According to experience, the warp threads shrink more on wetting at the edges of the material than in the centre of the fabric lengths.

It is of great importance for a successful result that the free fabric running on or running off the course indicated by line *a* and *b* between the fabric reel and the spreading out device or the fabric reel and the conveyor drum be as short as possible. In order that this may be attained, known mechanical, hydraulic or other means may be used in order to move upward or downward the reels 10, 11 in the direction of arrows *c* radial to the conveyor drum 1, the reels 10, 11 never, however, being adjusted so low that they come into contact with the conveyor drum 1 during the working process of the machine. The distance of the reel from the conveyor drum 1 is regulated according to the quantity of fabric on the reeling up or unwinding reel.

With electric drive, both the conveyor drum 1 and the running reels 10, 11 are driven by means of synchronous three-phase motors, the speed of which may be regulated by known means such as speed reducers, regulating resistances, and the direction of rotation of which may be altered by current reverses.

With the machine with mechanical drive (Figs. 4 and 5), the drive of the reels 10, 11, takes place from the shaft 2 through the toothed wheel gear 15, 16, 17, and friction discs 18, which are arranged on both sides. The fabric reels 10, 11 are driven through friction discs 19 which bear, according to the angle of inclination, with more or less pressure against the friction discs 18 by their own weight.

10 The rolling-off reel tends to be always raised by the friction disc 18 and is freely rotatable in ball bearings 12, rotating with minimum unwinding resistance which permits a high speed of the fabric length and consequently a large output from the machine. The transmission ratio between the shaft 2 and the friction disc 19 is slightly greater than that of the circumferences of the conveyor rollers 1 and of the fabric reels 10, 11, when the latter is empty.

15 What I wish to claim and secure by U. S. Letters Patent, is:—

In a dyeing machine for treating textile fabrics with liquids, comprising a container adapted to receive the liquid to treat the fabric, a positively driven feed drum arranged to immerse in the liquid in said container, two rollers disposed at both sides of said feed drum, separate and resilient means to drive said feed drum and each of said rollers, means to adjust the driving torque of said drum and of each of said rollers not to exceed a predetermined tension on the fabric, two buoyant cylinders within said container and disposed below and on both sides of the said feed drum, a frame, guide ways in said frame for said cylinders, the guide ways running in radial direction to said drum, an idle roller arranged between said cylinders at a distance from the mantle of the feed drum, means to reverse the direction of rotation of each of said rollers and of said drum, the said rollers being arranged to be close to but out of the liquid when fully wound, and a spreading device for the fabric arranged intermediate the drum and each of the rollers.

20 25 30 35 40 45 50 HANS WILLI METTLER.
